UNITED STATES PATENT OFFICE.

GEORGE LUDWIG, OF MILWAUKEE, WISCONSIN, ASSIGNOR TO MUTUAL METAL MANUFACTURING COMPANY, OF CHICAGO, ILLINOIS, A CORPORATION OF ILLINOIS.

DESIGN FOR A CHANDELIER.

Application filed March 16, 1928. Serial No. 25,880. Term of patent 3½ years.

To all whom it may concern:

Be it known that I, GEORGE LUDWIG, a citizen of the United States, residing at Milwaukee, in the county of Milwaukee and State of Wisconsin, have invented a new, original, and ornamental Design for a Chandelier, of which the following is a specification, reference being had to the accompanying drawing, forming part thereof.

Figure 1 is a perspective view of the device.

Figure 2 is a bottom view of the body plate thereof.

I claim:

The ornamental design for a chandelier, as shown.

GEORGE LUDWIG.
